COMBINATION UNDERGARMENT

Ermaline G. Neuhoff and Belle Fay Davenport,
Los Angeles, Calif.

Application August 28, 1945, Serial No. 613,114

2 Claims. (Cl. 2-29)

1

This invention relates to improvements in ladies' wearing apparel, and particularly to a combination undergarment.

The object of the invention is to provide a unitary combination undergarment comprising a brassière, girdle and skirt of such construction that the figure of the wearer will be firmly confined and given smooth lines as a foundation for the outer garment or dress.

Another object of the invention is to provide a garment as mentioned further characterized by a novel under-band to hold and reduce the heavy parts of the thigh, so that the dress will set well and strain on the dress will be avoided.

A further object of the invention is to provide a combination undergarment with an under-band as mentioned which, while firmly confining and reducing the hips, will be comfortable to wear and will not cut the thighs or front of the legs while sitting.

A further object of the invention is to provide a garment as mentioned which will be of sufficient strength to accomplish the foregoing objects and maintain its original dimensions and shape.

Other objects will appear hereinafter.

This invention will be more readily understood by reference to the accompanying drawings forming a part of this specification and in which:

Figure 1 is a front elevation of a garment embodying this invention, one side of the top being turned outwardly to more clearly show the construction.

Figure 2 is a rear elevation.

Figure 3 is a vertical cross section looking toward the front of the garment, and

Figure 4 is a detail vertical section from front to back through the under-band and adjoining parts.

Referring now to the drawings, the garment comprises generally a front panel 10 and a back panel 11 connected by side seams 12. The back panel is preferably formed of a single piece of material; whereas the front panel is formed of two sections 13 and 14. Each section 13 and 14 consists in an intermediate portion forming with the corresponding portion of the back panel, a girdle 15; a lower section which with the corresponding portion of the back completes a skirt 16; and an upper section constituting brassière portions 17-17. The girdle and skirt portions of each front section are formed of a single piece of material, but the brassière portions 17 are usually formed separately and felled to the top of the girdle section as at 18.

The upper edges of the brassière portions 17

2

are curved upwardly as at 19 and to the upper parts thereof are secured shoulder straps 20, the opposite ends of which are attached to the upper edge of the rear panel 11. The brassières may be shaped as desired, as by the felled seam 21 and darts 22.

The sections 13 and 14, below the girdle portions are connected by a felled seam 23 to complete an unbroken skirt. Above the skirt portion, the sections 13 and 14 of the front panel are provided with zipper fasteners 24, which extend upwardly to the ends of the felled seams 21 of the brassière. Above this point they are provided with other fastening means such as hook-and-eye fasteners 25. A protector flap 26 is provided on the edge of section 14 to guard against injury while operating the zipper, and to hold this flap in place. Hook-and-eye fasteners 27 are provided on said flap and the section 13 respectively. To give better support over the abdomen, the girdle portion is provided with stays 28 which are arranged in casings 29 which are stitched to the respective sections 13 and 14. Three or more horizontal darts 30 are provided to give both shape and strength to this portion of the device and, if preferred, vertical darts 31 may be made to further shape the garment. The back of the girdle portion is provided with a casing 32 in which are arranged stays 33.

Arranged on the inside of the garment is an underband 34 which constitutes one of the important features of this invention. This band is attached at its upper edge to the body of the garment at the junction of the girdle and skirt portions, by two or more rows of stitching 35. The band 34 is broad and is adapted to encircle the fleshy portions of the thighs or hips to compress and reduce the same, and to this end it tapers downwardly so the lower edge is of smaller girth than the upper edge where it is attached. To add strength to the band, the lower edge is provided with a hem 36 and two or more rows of stitching 37. At the front, for about one tenth of the circumference, the inelastic major portion of the band is discontinued, and is provided with an elastic trapezoidal insert 38 which is narrower at the top and flares toward the bottom edge. By this arrangement the lower edge of the band will not cut the thighs and front portions of the legs when the wearer is sitting.

Attached to the lower edge of the band 34, and assisting in holding the band 34 in place, are a plurality of hose fasteners or garters 39. These are preferably six in number and are arranged with three on each side of the garment—two in

front of the respective side seams 12, and one directly behind the same, as illustrated in Figure 4. These hose supporters 39 are of any ordinary or preferred construction, and are attached to the under-band by elastic loops 40 securely fastened to the lower edge thereof. The loops 40 are spread at their upper ends to distribute their pull over a large portion of the band.

In order to give additional strength to the garment, the several panels and sections, as well as the under-band are cut with the warp of the goods horizontal, or so as to encircle the body. This is a much stronger construction, and will not pull out or stretch as will material cut with the warp threads vertical and the strains applied transversely thereto.

We claim:

1. In a combination garment, a girdle portion and a skirt portion substantially inelastic in girth, said skirt portion being a continuation of the girdle portion in combination with an under-band adapted to encircle the fleshy portions of the thighs and hips, stitching connecting the upper edge of said underband to the skirt portion at substantially the area of greatest girth of said fleshy portions, said band comprising a major portion of substantially inelastic material and a shorter elastic insert at substantially the front of said underband, an inelastic seam connecting the upper edge of said band to the garment, and the girth of the lower edge of the band being smaller than said upper edge to engage said fleshy portions below the area of greatest girth.

2. A combination undergarment comprising a front panel and a one piece back panel, the front panel formed of two similar sections each consisting of an intermediate girdle portion, an upper brassière portion and a lower skirt portion, said back and front panels having the warp of the goods extending horizontally, felled seams connecting the front panel sections to the back panel, and felled seams connecting the skirt portions of the front sections forming an unbroken skirt, separable fasteners connecting the adjacent edges of the girdle portions and of the brassière portions, a plurality of horizontal darts in the front girdle portions tapering laterally from the vertical front edges of said girdle portions, casings secured to the inner faces of said girdle portions and covering the area of said horizontal darts, stays in said casings, and darts in said front girdle sections adjacent said stays and substantially parallel therewith.
